US00D934560S

(12) United States Design Patent (10) Patent No.: US D934,560 S
Tran et al. (45) Date of Patent: * Nov. 2, 2021

(54) WALLET

(71) Applicants: Thuan Tran, Santa Clara, CA (US);
Charlie Carroll, Palo Alto, CA (US);
Binh Tran, Santa Clara, CA (US)

(72) Inventors: Thuan Tran, Santa Clara, CA (US);
Charlie Carroll, Palo Alto, CA (US);
Binh Tran, Santa Clara, CA (US)

(73) Assignee: Dango Products, LLC, Portola Valley, CA (US)

() Term: 15 Years

(21) Appl. No.: 29/732,095

(22) Filed: Apr. 21, 2020

(51) LOC (13) Cl. 03-01

(52) U.S. Cl.

USPC D3/247

CLAIM

The ornamental design for a wallet, as shown and described.

DESCRIPTION

FIG. 1 is a front view of a wallet.

FIG. 2 is a rear view of the wallet.

FIG. 3 is a top view of the wallet.

FIG. 4 is a bottom view of the wallet.

FIG. 5 is a left side view of the wallet.

FIG. 6 is a right side view of the wallet.

FIG. 7 is a perspective front view of the wallet; and,

FIG. 8 is a perspective rear view of the wallet.

1 Claim, 8 Drawing Sheets
